**3,5-DIOXA-12-AZAWURTZITANE
COMPOUND AND PROCESS OF PREPARING
SAME**

Matter enclosed in heavy brackets [ ] appears in the original patent but forms no part of this reissue specification; matter printed in italics indicates the additions made by reissue.

BACKGROUND OF THE INVENTION

This invention relates to a 3,5-dioxa-12-azawurtzitane compound and a process of preparing same. The new class of dioxa-azawurtzitane compounds of the present invention have a structure similar to an amino acid or a polypeptide and will be utilizable for various applications, for example, as a molecular recognition agent for use in neurotransmission studies, an intermediate for a protein-resembling compound, a surfactant, a protective group and a host-guest complex for use as a sensor.

A dioxa-azawurtzitane of the following formula is reported by Hiroshi IZUMI and Shigeru FUTAMURA in J. Chem. Soc., Perkin Trans. 1, 1925 (1998):

in which Me stands for a methyl group and R stands for a 4-methoxybenzyl group, a 2-(pyridin-2-yl)ethyl group or a 2-(imidazol-4-yl)ethyl group. The known wurtzitane compounds do not have a structure similar to an amino acid or a polypeptide.

SUMMARY OF THE INVENTION

It is an object of the present invention to provide a 3,5-dioxa-12-azawurtzitane compound having a structure similar to an amino acid or a polypeptide.

In accordance with one aspect of the present invention, there is provided a 3,5-dioxa-12-azawurtzitane compound represented by the following formula (I):

-continued

wherein R¹ represents an alkyl group, R² represents a group which, together with a —CH(NH₂)COOH group, constitutes an α -amino acid of the formula R²CH(NH₂)COOH and which may contain one or more substituents and R³ represents a hydroxyl group or a group obtained by removing a hydrogen atom of the terminal amino group of an oligo- or polypeptide or a polyamino acid.

In another aspect, the present invention provides a process of preparing a 3,5-dioxa-12-azawurtzitane compound represented by the following formula (I):

wherein R¹ represents an alkyl group, R² represents a group which, together with a —CH(NH₂)COOH group, constitutes an α -amino acid of the formula R²CH(NH₂)COOH and which may contain one or more substituents and R³ represents a hydroxyl group or a group obtained by removing a hydrogen atom of the terminal amino group of an oligo- or polypeptide or a polyamino acid, said process comprising reacting an amino acid, an oligo- or polypeptide or a polyamino acid with a trialdehyde represented by the following formula (II):

wherein R¹ has the same meaning as above.

In the present specification and claims, the three R¹s bonded to the carbon atoms at 1-, 7- and 9-positions of the

3,5-dioxa-12-azawurtzitane compound of the formula (I) or at 1-, 3- and 5-positions of the trialdehyde of the formula (II) may be the same or different alkyl groups.

Other objects, features and advantages of the present invention will be apparent from the detailed description of the preferred embodiments of the invention to follow.

DETAILED DESCRIPTION OF THE PREFERRED EMBODIMENTS OF THE INVENTION

A 3,5-dioxa-12-azawurtzitane compound of the present invention is represented by the above formula (I). In the formula (I), R¹ represents an alkyl group preferably having 1-12 carbon atoms. Illustrative of suitable alkyl groups of R¹ are methyl, ethyl, propyl, butyl, pentyl, hexyl, heptyl, octyl, nonyl, decyl and structural isomers thereof.

The symbol R² represents a group which, together with a —CH(NH₂)COOH group, constitutes an α -amino acid of the formula R²CH(NH₂)COOH. Examples of the α -amino acids R²CH(NH₂)COOH include glycine (Gly), alanine (Ala), Valine (Val), leucine (Leu), Isoleucine (Ileu), phenylalanine (Phe), tyrosine (Tyr), tryptophan (Try), serine (Ser), threonine (Thre), cystein (CySH), cystine (CyS-SCy), methionine (Meth), aspartic acid (Asp), glutamic acid (Glu), lysine (Lys), arginine (Arg) and histidine (His). The group R² may contain one or more substituents such as an alkyl group, an acetyl group, an alkoxy group, a benzoxy carbonyl group, a tert-butoxycarbonyl group, a 9-fluorenylmethoxycarbonyl group and a 1,7,9-triethyl-3,5-dioxa-12H-azawurtzitan-12-yl group.

The symbol R³ represents a hydroxyl group or a group obtained by removing a hydrogen atom of the terminal amino group of an oligo- or polypeptide or a polyamino acid.

Some examples of 3,5-dioxa-12-azawurtzitane compounds of the present invention are shown in Table 1 in which R¹, R² and R³ are the symbols of the formula (I). The 3,5-dioxa-12-azawurtzitane compounds of the present invention, however, are of course not limited to those specifically exemplified compounds. For example, the groups R¹, R² and R³ listed in Table 1 may be arbitrarily selected for any desired combination.

TABLE 1

R ¹	R ²	R ³
CH ₃	H	(His) _n
CH ₃	CH ₃	(Gly) _n
CH ₃ CH ₂	(CH ₃) ₂ CH	(Ala) _n
CH ₃ CH ₂ CH ₂	(CH ₃) ₂ CHCH ₂	(Val) _n
CH ₃ (CH ₂) ₃	CH ₃ CH ₂ (CH ₃)CH	(Leu) _n
CH ₃ (CH ₂) ₄		(Phe) _n
CH ₃ (CH ₂) ₅		(Tyr) _n
H		(Try) _n

TABLE 1-continued

R ¹	R ²	R ³
(CH ₃) ₂ CH	HOCH ₂	(Ser) _n
(CH ₃) ₂ C	CH ₃ (OH)CH	(Thre) _n
(CH ₃) ₂ CHCH ₂	HSCH ₂	(CySH) _n
(CH ₃) ₂ CH(CH ₂) ₂	HOOC(NH ₂)CH CH ₂ SSCH ₂	(CyS-SCy) _n
(CH ₃) ₃ C(CH ₂) ₃	CH ₃ SCH ₂ CH ₂	(Meth) _n
CH ₃ CH ₂ CH ₂	HOOCH ₂	(Asp) _n
CH ₃ (CH ₂) ₃	HOOCC ₂ CH ₂	(Glu) _n
CH ₃	H ₂ NCH ₂ (CH ₂) ₃	(Lys) _n
CH ₃	HN=C(NH ₂)NH(CH ₂) ₃	(Arg) _n
CH ₃		OH

In Table 1, n is an integer.

The 3,5-dioxa-12-azawurtzitane compounds of the formula (I) may be prepared by reacting a trialdehyde of the formula (II) with an amino acid, an oligo- or polypeptide or a polyamino acid. The reaction is as follows:

The trialdehyde of the formula (II) may be obtained by any known method such as a method described in Hiroshi IZUMI and Shigeru FUTAMURA, J. Org. Chem. vol. 64, 4502 (1999), the disclosure of which is hereby incorporated by reference herein.

The raw material to be reacted with the trialdehyde of the formula (II) may be expressed by the following formula (III):

wherein Z represents an amino acid and n is an integer of 1 or more with the proviso that, when n is two or more, the amino acids may be the same or different.

Any amino acid may be used as Z of the formula (III). Examples of amino acids include glycine (Gly), alanine (Ala), Valine (Val), leucine (Leu), Isoleucine (Ileu), phenylalanine (Phe), tyrosine (Tyr), tryptophan (Try), serine (Ser), threonine (Thre), cystein (CySH), cystine (CyS-SCy), methionine (Meth), aspartic acid (Asp), glutamic acid (Glu), lysine (Lys), arginine (Arg) and histidine (His). Any oli-

opeptide (composed of 2 to 9 amino acids), polypeptide (composed of 10 or more amino acids) or polyamino acid (composed of two or more amino acids) may be used as a raw material for the above reaction.

Preferably, the reaction may be performed by mixing an aqueous solution of an amino acid, an oligo- or polypeptide or a polyamino acid with an organic polar solvent solution of the trialdehyde of the formula (II), and reacting the resulting mixture at a temperature and for a period of time sufficient to produce the desired 3,5-dioxa-12-azawurtzitane compound. The trialdehyde is generally used in a stoichiometric amount. The aqueous solution may be a buffer solution. The organic polar solvent may be an aprotic one compatible with water, such as acetone or acetonitrile. The reaction is preferably carried out at 0-70° C. for 0.5-24 hours.

The following examples will further illustrate the present invention.

EXAMPLE 1

An acetone solution containing 56 mg of a trialdehyde of the formula (II) was mixed with an aqueous solution containing 51 mg of 3-methyl-L-histidine and the mixture was reacted at room temperature for 2 hours with stirring. The crude product was extracted and purified by chromatography to obtain 90 mg (yield: 94%) of 3,5-dioxa-12-azawurtzitane compound of the formula (I) in which R¹ is a methyl group, R² is a (1-methylimidazol-4-yl)methyl group and R³ is a hydroxyl group. The results of the NMR analysis of the product are shown below.

¹H NMR (acetone-d₆): δ 0.78 (d, 1H, J=11.9 Hz, methylene H), 0.89 (d, 2H, J=12.1 Hz, methylene H), 0.95 (s, 3H, methyl H), 0.99 (s, 3H, methyl H), 1.01 (s, 3H, methyl H), 1.33 (d, 2H, J=12.1 Hz, methylene H), 1.43 (d, 1H, J=11.9 Hz, methylene H), 3.15 (dd, 1H, J=15.5 Hz, J=9.3 Hz, methylene H), 3.35 (dd, 1H, J=15.5 Hz, J=4.5 Hz, methylene H), 3.65 (s, 3H, imidazole methyl H), 4.24 (dd, 1H, J=9.3 Hz, J=4.5 Hz, methine H), 4.34 (s, 1H, wurtzitane methine H), 4.46 (s, 1H, wurtzitane methine H), 4.74 (s, 1H, wurtzitane methine H), 6.76 (s, 1H, imidazole H), 7.38 (s, 1H, imidazole H).

EXAMPLE 2

An acetone solution containing 10 mg of a trialdehyde of the formula (II) was mixed with an aqueous solution containing 14 mg of a peptide Gly-Gly-His and the mixture was reacted at room temperature for 2 hours with stirring. The crude product was extracted and purified by chromatography to obtain 17 mg (yield: 82%) of 3,5-dioxa-12-azawurtzitane compound of the formula (I) in which R¹ is a methyl group, R² is a hydrogen atom and R³ is a Gly-His residue. The results of the NMR analysis of the product are shown below.

¹H NMR (acetone-d₆/D₂O): δ 0.75 (d, 1H, J=12.2 Hz, methylene H), 0.81 (d, 2H, J=11.6 Hz, methylene H), 0.90 (s, 3H, methyl H), 0.94 (s, 3H, methyl H), 0.94 (s, 3H, methyl H), 1.23 (d, 2H, J=11.6 Hz, methylene H), 1.57 (d, 1H, J=12.2 Hz, methylene H), 3.00 (dd, 1H, J=15.3 Hz, J=7.3 Hz, methylene H), 3.16 (dd, 1H, J=15.3 Hz, J=4.9 Hz, methylene H), 3.71 (d, AB, 1H, J=17.1 Hz, methylene H), 3.77 (d, AB, 1H, J=17.1 Hz, methylene H), 3.86 (d, AB, 1H, J=16.9 Hz, methylene H), 3.91 (d, AB, 1H, J=16.9 Hz, methylene H), 4.06 (s, 1H, wurtzitane methine H), 4.08 (s, 1H, wurtzitane methine H), 4.37 (dd, 1H, J=7.3 Hz, J=4.9 Hz, methine H), 4.69 (s, 1H, wurtzitane methine H), 7.16 (s, 1H, imidazole H), 8.41 (s, 1H, imidazole H).

The invention may be embodied in other specific forms without departing from the spirit or essential characteristics

thereof. The present embodiments are therefore to be considered in all respects as illustrative and not restrictive, the scope of the invention being indicated by the appended claims rather than by the foregoing description, and all the changes which come within the meaning and range of equivalency of the claims are therefore intended to be embraced therein.

What is claimed is:

1. A 3,5-dioxa-12-azawurtzitane compound represented by the following formula (I):

wherein [R³] R¹ represents an alkyl group, R² is selected from the group consisting of hydrogen, the following members:

and said members substituted with one or more of alkyl, acetyl, alkoxy, benzoxy carbonyl, tert-butoxy carbonyl, 9-fluorenylmethoxy carbonyl, and 1,7,9-triethyl-3,5-dioxa-12H-azawurtzitan-12-yl, and R³ is selected from the group consisting of hydroxyl, oligopeptides, polypeptides, *amino acids* and polyamino acids, provided that where R³ is an oligopeptide, polypeptide, *amino acid* or polyamino acid it is linked through a terminal amino group.

2. A process of preparing a 3,5-dioxa-12-azawurtzitane compound represented by the following formula (I):

wherein R¹ represents an alkyl group, R² is selected from the group consisting of hydrogen, the following members:

and said members substituted with one or more of alkyl, acetyl, alkoxy, benzoxy carbonyl, tert-butoxy carbonyl, 9-fluorenylmethoxy carbonyl and 1,7,9-trialkyl-3,5-dioxa-12H-azawurtzitan-12-yl, and R³ is selected from the group consisting of hydroxyl, oligopeptides, polypeptides, amino acids and polyamino acids, provided that where R³ is an oligopeptide, a polypeptide, an amino acid or a polyamino acid, it is linked through a terminal amino group, said process comprising reacting an amino acid, an oligo- or polypeptide or a polyamino acid with a trialdehyde represented by the following formula (II):

wherein [R1] R¹ has the same meaning as above.

35 3. A process as claimed in claim 2, comprising mixing an aqueous solution of said amino acid, [an] oligo- or polypeptide or [a] polyamino acid with an organic polar solvent solution of said trialdehyde, and reacting the resulting mixture at a temperature and for a period of time sufficient to 40 obtain said 3,5-dioxa-12-azawurtzitan compound.
